UNITED STATES PATENT OFFICE.

LOUIS ANDERSON, OF CHICAGO, ILLINOIS.

HARVESTING-MACHINE.

1,143,161.

Specification of Letters Patent. Patented June 15, 1915.

Application filed July 5, 1912. Serial No. 707,812.

To all whom it may concern:

Be it known that I, LOUIS ANDERSON, a citizen of the United States, and resident of Chicago, county of Cook, and State of Illinois, have invented certain new and useful Improvements in Harvesting-Machines, of which the following is a specification, and which are illustrated in the accompanying drawings, forming a part thereof.

10 The invention relates to harvesting machines, and more particularly to those having provision for reaping and binding grain and for collecting the bundles and depositing them upon the ground in the form of a shock.

15 The present invention contemplates improved mechanism for controlling the operation of the several parts.

20 The object of the invention is to provide a harvesting machine which shall be of simple construction and reliable in operation.

25 The invention is exemplified in the structure to be hereinafter described, and which is illustrated in the accompanying drawings, wherein—

Figure 1 is a side elevation of a harvesting machine embodying the features of improvement provided by the invention; Fig. 2 is a detail plan view of the same; Fig. 3 is a detail rear elevation of the machine, the rear end sill of the frame being omitted and some of the parts being shown in section; Fig. 4 is a detail front elevation of the machine, the front end sill of the frame being omitted and the adjacent portions of the side sills being shown in section; Figs. 5 and 6 are sectional views taken on the lines 5—5 and 6—6 respectively of Fig. 2; Fig. 7 is a detail sectional view taken on the line 7—7 of Fig. 6; Fig. 8 is a detail plan sectional view taken on the line 8—8 of Fig. 4; Fig. 9 is an end elevation of the bundle-gripping mechanism, the position of this view being indicated by the arrow 9 on Fig. 2; Fig. 10 is similar to Fig. 9, but shows the parts in the position which they occupy when holding the bundle; and Fig. 11 is a detail rear elevation of the machine showing the parts of the bundle transfer mechanism in the position which they occupy immediately after releasing a bundle and permitting it to fall into the shock-forming mechanism.

55 The parts of the machine are shown as being associated upon an oblong rectangular frame comprising the side sills 25, 26, the

rear end sill 27 and the front end sill 28. The frame is principally supported upon a traction wheel 29 which is located at about the mid-length of the frame between the side sills 25, 26.

The bundles of grain are formed in the usual way upon an inclined table shown at 30. This table is supported over the frame, as by the uprights 31, 32, 33 and 34. Belt 65 conveyer mechanism for delivering the loose grain to the table 30 is shown at 35. During the formation of the bundles, the loose grain is forced against a movable trip arm 36 by the packers 37 and 38, and is tied 70 by the knotted mechanism comprising the needle arm 39 and the knotted shaft 40. When a sufficient amount of grain for the formation of a bundle has been forced against the trip arm 36, this arm is depressed. As is usual in the operation of 75 harvesting machines, the movement of this arm automatically arrests the operation of the packers 37, 38 and sets the knotted shaft 40 in motion.

80 A pair of guide arms 42, 43 are provided for receiving each bundle of grain after it is tied. As shown these arms project laterally from the lower edge of the table 30. Each bundle of grain, after being completed, is pushed outwardly upon these arms. For this purpose an arm 41, carried by the 85 knotted shaft 40 and projecting radially outward therefrom, is preferably provided.

Most desirably the tying of each bundle 90 of grain and the movement of the bundle outwardly upon the guide arms 42, 43 by the engagement therewith of the arm 41, are both completed during a single rotation of the knotted shaft. To this end the arm 41 95 is preferably so positioned upon the knotted shaft as to engage the bundle during the latter part of each rotation of the shaft.

Power for actuating the several parts of the machine may be supplied in any convenient way, as from the traction wheel 29. As shown, a countershaft 44 extends transversely between the sills 25, 26 and is journaled upon the inside faces of these sills at its opposite ends. This countershaft is 100 operatively connected with the traction wheel 29 by a sprocket chain 45. This sprocket chain turns over a sprocket wheel 46 mounted with the traction wheel and over a sprocket wheel 47 mounted on the 105 countershaft. A second shaft 48, connected to the countershaft 44 by beveled gears 49,

50, extends to the forward end of the machine for actuating the knot-forming mechanism as also the reaping mechanism (not shown). A pair of beveled gears 51, 52, 5 most clearly shown in Fig. 8, are mounted on the shaft 48 adjacent its forward end. The gear 51 is fixed upon the shaft 48 to rotate with the shaft. The gear 52 is normally loose upon the shaft. The gear 51 10 serves to transmit power to the packers 37, 38. The gear 52 serves to transmit power to the knotter shaft 40.

A beveled pinion 53 meshes with the gear 51. This pinion is mounted upon the lower 15 end of a flexible shaft 54. The higher end of this shaft is connected by beveled gears 55, 56 with a shaft 57 which actuates the packers 37, 38 in the usual way. The lower end of the shaft 54, adjacent the pinion 53, 20 is journaled in a swinging arm 60 (Fig. 8), whereby the pinion 53 may be moved into and out of engagement with the beveled gear 51. As shown the arm 60 is mounted upon an upright pivot 61 which rises from 25 a bracket 62 carried by the side sill 26.

For operatively connecting the beveled gear 52 with the knotter shaft 40 a shaft 63 is provided. This shaft has beveled pinions 64, 65 mounted upon its opposite 30 ends for meshing with the beveled gear 52 and with a beveled gear 66 on the knotter shaft 40, respectively. A ratchet wheel 67 is fixed upon the shaft 48 adjacent the hub of the beveled gear 52. A pawl 68, mounted 35 upon the back of the beveled gear 52, serves to engage this ratchet wheel when the knotter shaft is to be driven. The pawl 68 is normally held out of engagement with the ratchet wheel 67 by a cam finger 69. 40 This cam finger is preferably carried by the swinging arm 60, whereby when the arm 60 is swung to move the beveled pinion 53 out of engagement with the beveled gear 51 and thereby arrest the operation of the packers 45 37, 38, the cam finger 69 is withdrawn from beneath the pawl 68. When the arm 60 is moved back to its original position to restore the pinion 53 to its position of engagement with the gear 51, the cam finger 50 69 is again brought into the path of the pawl 68. The pawl 68 will then be raised out of engagement with the ratchet wheel 67, to arrest the movement of the knotter shaft 40, as soon as the pawl reaches the 55 cam during the turning of the shaft.

A toggle 70 serves for swinging the arm 60. This toggle is connected at one end to the swinging arm 60 and at the other end to a fixed part of the frame of the machine, 60 as to the cross tie 71. A shipper rod 72 is connected at one end to the joint of the toggle 70 and at the other end to the crank arm 73 of a rock shaft 74. The rock shaft 74 extends longitudinally beneath the table 65 30. It is turned in one direction to release

the pinion 53 from engagement with the beveled gear 51 and to set the knot-forming shaft 40 in motion by the movement of the trip arm 36 heretofore described. To this end the trip arm 36 extends downwardly 70 through the table 30 and is mounted at its lower end on a rock shaft 75. The rock shaft 75 carries a crank arm 76 for engaging a yoke 77 which is carried by the rock shaft 74 and projects radially therefrom. Preferably the crank arm 76 is jointed, as shown at 75 58, whereby its lower end will yield in one direction. As shown the crank arm and yoke are so proportioned in length that when the trip arm 36 is depressed, the crank 80 arm 76 engages the cross arm of the yoke 77 to swing the rock shaft 74, and then passes beyond this cross arm and into the space inclosed by the yoke. This arrangement permits the rock shaft 74 to be restored to 85 its original position in advance of the restoration of the trip arm 36. When the trip arm 36 is to be restored, the jointed arm 76 flexes to permit its lower end to pass over the cross member of the yoke 77. 90

A cam 78 mounted on the knotter shaft 40 serves to move the rock shaft 74 in the direction to restore the pinion 53 into engagement with the gear 51 and to bring the cam finger 69 into the path of the pawl 68. 95 A bell crank lever 79 has one of its arms extending into the path of the cam 78 and its other arm connected by a link 80 to a crank arm, as 81, of the rock shaft 74. For convenience the bell crank lever 79 is pivotally mounted upon the spindle, as 82, of the needle arm 39. 100

The shock-forming mechanism comprises a cradle generally designated by the numeral 83. This cradle serves to receive the bundles of grain and to retain them until a sufficient number for the formation of a shock have accumulated therein. For transferring the bundles of grain from the arms 42, 43, to the cradle 83, a swinging arm 84, carrying a fork 86 is provided. As shown this arm, as also an operating arm 85 extending parallel therewith, is mounted in the head 87 of a rotatable post 59. As a means for supporting the rotatable post 59, it is shown as being extended through a tubular standard 88. This standard is preferably located near the rear lower corner of the table 30. As shown, it is carried by a bracket 89 mounted on said table. 110 115

The fork 86 comprises a forked abutment member 90 and a similarly formed grasping member 91. To permit the bundle to be turned end for end the fork 86 is rotated upon its axis. To this end the abutment 125 member 90 has a vertically extended stem 92. This stem extends through and is rotatably mounted in a journal bearing 93 located upon the outer end of the arm 84. The grasping member 91 is pivoted at 94 130

upon a bracket 95 carried by the abutment member 90. A spring 96, reacting between the head of the member 91 above the pivot 94, and a second bracket 97 carried by the 5 abutment member 90, serves to normally hold the parts of the fork in open position.

The arms 84, 85 normally stand in the position shown in Fig. 5 of the drawings, whereby the abutment member 90 is held in 10 a suitable position to serve as a stop against which the bundle of grain is moved by the arm 41. The grasping member 91 is preferably closed upon the bundle of grain by rotating the arm 85. As shown, the arm 85 15 carries a crank arm 98 adjacent its outer end, and this crank arm bears upon a cam member 99 which is carried by the bundle grasping member 91. For holding the grasping member 91 in closed position during 20 the axial rotation of the fork 86, a cam track 100 is provided for engaging the head portion 101 of the grasping member 91. The cam track 100 is conveniently carried by a bracket arm 102 which in turn is mounted 25 upon the outer end of the arm 84.

To prevent the bundle of grain from being thrown to the rear of the shock-forming cradle 83 when it is released from the fork 86, provision is preferably made for 30 releasing the bundle after the fork has been brought to rest in a position above the cradle. This is conveniently accomplished by making the cam track 100 sectional, an end portion 103 of the same being hinged, 35 as at 104, to swing upwardly. For controlling the swinging of the end portion 103 of the cam track 100, a lever 105 is pivotally mounted upon the bracket 102 intermediate its ends. One end of this lever is connected 40 to the part 103 by a link 106. The other end of the lever 105 is connected by a link 107 to the crank arm 98. A rotation of the arm 85 in the proper direction to raise the crank arm 98 also raises the part 103 to permit the 45 bundle of grain to fall from the fork 86. For rotating the fork 86 to turn the bundle end for end a crank arm 108 is mounted upon the higher end of the stem 92. A link 110 connects this crank arm with a fixed 50 part of the frame of the machine, as the bracket 109.

Inasmuch as a bundle of grain is carried in the fork 86 during its movement in one direction only, the arm 84 is preferably extended in rear of the head 87, and a sliding counterweight 111 is mounted on this part of the arm. The sliding of this counterweight, as also the turning of the arm 85, is preferably effected by means of a plunger 112 which extends vertically through the post 59. A bell crank lever 113, pivoted at 114 upon a part of the head 87, is employed for operatively connecting the plunger 112 with the sliding counterweight 111. One 65 arm of this bell crank lever has a pin and

slot connection 115 with the plunger 112. The other arm of the bell-crank lever 113 is connected to the counterweight 111 by a link 116. A crank arm 117, mounted on the arm 85 adjacent its inner end, is connected to the 70 plunger 112 by a link 118. The arrangement provides that a vertical reciprocation of the plunger 112 within the post 59 simultaneously moves the counterweight 111 upon the extended rear end of the arm 84 and 75 turns the arm 85 to cause the fork 86 to grasp or release a bundle of grain. By this means the counterweight 111 is moved outwardly whenever the fork 86 receives the weight of a bundle of grain, and is moved 80 inwardly whenever the fork 86 is relieved of the weight of a bundle of grain.

A pair of cams 119, 120, are provided for reciprocating the plunger 112 and for turning the tubular post 59, respectively. As 85 shown, these cams are formed integral and upon the opposite faces of a cam plate 121. The cam plate 121 is fixed upon a sleeve 122. This sleeve is loosely mounted on the countershaft 44. Clutch mechanism is provided 90 for causing the sleeve 122 to turn with the countershaft 44 when the bundle transfer mechanism is to be operated. As shown, this clutch mechanism comprises a ratchet 123, a pawl 124, and a pawl lifter 125. The 95 ratchet 123 is formed upon the hub of the sprocket wheel 47 and moves continuously with the sprocket wheel 47 and with the shaft 44. The pawl 124 is carried by the sleeve 122 and co-operates with the ratchet 100 123 to turn the sleeve 122 with the countershaft 44 through one complete revolution whenever the bundle transfer mechanism is to be operated. The pawl lifter 125 takes the form of a cam finger having one end 105 resting upon the hub of the ratchet wheel 123. This cam finger is pivoted intermediate its ends upon a fixed part of the frame of the machine, as upon the bracket 126 (Fig. 7). Normally the pawl 124 rests upon 110 the free end portion of the cam finger 125, and is held thereby out of engagement with the ratchet 123. A spring 125^a, reacting between the cam finger 125 and the bracket 115 126, may be used to normally hold the cam finger in position to support the pawl.

When the bundle transfer mechanism is to be operated, the cam finger 125 is swung about its pivot to withdraw its free end from beneath the pawl 124. For this purpose the cam finger 125 is connected by a link 127 to the crank arm 128 of a rock shaft 129. This rock shaft extends beneath the table 30 to the forward end of the machine. At its forward end it carries a crank arm 125 130 (Fig. 4). This crank arm extends upwardly to a position adjacent the knoter shaft 40 and co-operates with a cam, as 78, mounted on the knoter shaft. The rock shaft 129 is thereby oscillated to withdraw 135

the cam finger 125 from beneath the pawl 124 at a predetermined point in the movement of the knotter shaft. When the sleeve 122 has been turned through one complete revolution, the cam finger 125 having been returned to its original position by the spring 125^a, the pawl 124 rides upon this cam finger and is lifted thereby out of engagement with the ratchet wheel 123, and the sleeve 122 comes to rest.

A pair of vertically movable plungers 131, 132, are provided for coöperating with the cams 119, 120, respectively. Each of these plungers has its lower end bifurcated, as indicated at 133 (Fig. 7), to straddle the sleeve 122 and to be guided thereby. Cam rollers 134, 135, carried by the plungers 131, 132, respectively, coöperate with the cams 119 and 120 for effecting a vertical reciprocation of the plungers 131 and 132 during the turning of the sleeve 122.

The plunger 131 serves for vertically reciprocating the plunger 112. To this end the plunger 131 has its higher end operatively connected to a lever 136. This lever is pivoted intermediate its ends upon a fixed part of the frame of the machine, as at 137 (Fig. 3). The other end of the lever 136 is connected to the lower end of the plunger 112 by a link 138.

The plunger 132 serves for turning the post 59 within the standard 88. To this end a crank arm 139, most clearly shown in Fig. 2, is mounted upon the lower end of the post. This crank arm is connected to one end of a lever 140, as by a link 141. The lever 140 is pivoted intermediate its ends upon a fixed part of the frame of the machine, as upon the bracket 142 (Fig. 3). The other end of the lever 140 is operatively connected to the plunger 132, as by a bell-crank lever 143. This bell-crank lever oscillates in a vertical plane and is pivotally mounted upon any convenient part of the frame of the machine, as upon a bracket 144, secured to the under side of the table 30.

Preferably the swinging of the lever 140 serves to restore the trip arm 36 to its upright position. For this purpose a lever 145 may be provided. As shown, this lever is pivotally mounted upon the under side of the table 30, as at 146 (Fig. 5). One end of the lever extends into the path of the lever 140, to be engaged by the last-named lever when the post 59 has been rotated to remove a bundle of grain from the arms 42, 43. The other end of the lever 145 is connected to a crank arm 147 of the rock shaft 75 by a link 148.

The operation of the machine, as shown, is as follows: As the machine is drawn over the ground the countershafts 44 and 48 are continuously rotated by the turning of the traction wheel 29. Loose grain is fed to the table 30 by the belt conveyer mechanism 35.

The grain is then moved against the trip arm 36 by the packers 37, 38, in a well known manner. When a sufficient quantity of grain has accumulated for the formation of a bundle, the trip arm 36 is depressed and rotates the rock shaft 75. This throws the lower end of the crank arm 76 (Fig. 4) against the yoke 77 and turns the rock shaft 74. The turning of this rock shaft moves the shipper rod 72 and swings the arm 60 (Fig. 8) by flexing the toggle 70. This withdraws the pinion 53 from engagement with the beveled gear 51 and arrests the action of the packers 37, 38. It also withdraws the cam finger 69 from beneath the pawl 68, whereby the pawl is permitted to fall into engagement with the ratchet wheel 67 to rotate the beveled gear 52 and drive the knotted shaft 40. The turning of the knotter shaft 40 actuates the needle arm 39 to tie a bundle of grain. When the bundle has been completely formed, it is engaged by the arm 41 (Fig. 5) and thrust out upon the arms 42, 43, and into engagement with the abutment member 90 of the fork 86 of the bundle transfer mechanism. During the formation of the bundle of grain the cam 78 swings the bell crank lever 79, and turns the rock shaft 74 to restore the yoke 77 to its normal position and to restore the arm 60 (Fig. 8) to that position in which the pinion 53 is engaged with the beveled gear 51. This renews the actuation of the packers 37, 38, and the cam finger 69 having been moved back into the path of the pawl 68, this pawl will be raised out of engagement with the ratchet wheel 67 to arrest the movement of the knotter shaft when the beveled gear 52 has been turned through one complete revolution. When a bundle of grain has been brought against the abutment part 90 of the fork 86 of the bundle transfer mechanism, the cam 78 will have engaged the lever 130 (Fig. 4) to turn the rock shaft 129 and withdraw the pawl lifter 125 (Fig. 6) from beneath the pawl 124. The sleeve 122 and cams 119 and 120 are thus actuated through one complete revolution and drive the bundle transfer mechanism. The cam 119 first causes the plungers 131 and 132 (Fig. 3) to be shifted to close the part 91 (Fig. 9) upon the bundle and to move the counterweight 111 outwardly upon the extended rear end portion of the arm 84. The cam 120 then actuates the plunger 132 to rotate the post 59 and swing the fork to a position above the shock-forming cradle 83. During this movement of the fork 86, the bundle of grain is turned end for end by the turning of the fork upon its pivot, this being accomplished by the connection of the crank arm 108 with the fixed part 109 (Fig. 1) through the link 110. As the bundle is being moved to a position over the cradle 83, the parts of the fork 86 are held in closed 130

position by the engagement of the cam track 100 (Fig. 10) with the head 101 of the grasping member 91. When the bundle of grain has been brought to rest in a position 5 above the cradle 83, the cam 119 again shifts the plungers 131 and 112 to move the counterweight 111 inwardly and raise the movable end portion 103 of the cam track 100 (Fig. 11) to permit the parts of the fork 10 86 to be opened by the action of the spring 96. The bundle of grain thereupon falls into the shock-forming cradle 83. The cam 120 now actuates the plunger 132 to return the fork 86 to its position for receiving another 15 bundle of grain. As soon as the fork 86 has removed one bundle of grain from the arms 42, 43, the trip arm 36 is restored to its upright position by the engagement of the lever 140 with the lever 145 (Fig. 2). This 20 permits the operation of the bundle forming mechanism to be continued for the formation of a new bundle, while the previously formed bundle is being transferred to the shock former 83. In event the new bundle 25 has been completed by the time the fork 86 is returned to its bundle-receiving position, the sleeve 122 will continue to rotate and the operation of the parts will be repeated without interruption. If a new bundle of 30 grain has not been completed at the time indicated, the pawl 124 will ride upon the cam finger 125 when the sleeve 122 has been turned through one complete revolution, thereby bringing the parts of the bundle 35 transfer mechanism to rest until the trip arm 136 is again depressed. When a sufficient number of bundles of grain for the formation of a shock have been transferred to the cradle 83, this mechanism will be operated to deposit the bundles upon the 40 ground in the form of a shock in a manner which is fully described in my copending application for patent on shock former for harvesting machines, Serial No. 693,984, 45 filed April 29, 1912.

I claim as my invention—

1. In a harvesting machine in combination, a yielding abutment, feed mechanism for moving loose grain against said abutment, bundle tying mechanism, a drive shaft, connection between the drive shaft and the said feed mechanism including a clutch, means for driving the bundle tying mechanism including a wheel loose on the 50 said drive shaft a pawl carried by the said wheel and a ratchet fixed on the said drive shaft for coöoperating with the pawl to turn the said wheel, a pawl lifter, means operated by the said yielding abutment and acting to

open the said clutch and withdraw the said 60 pawl lifter and a cam turned by the said bundle tying mechanism for closing the said clutch and resetting the said pawl lifter.

2. In a harvesting machine in combination, a yielding abutment, feed mechanism 65 for moving loose grain against said abutment, bundle forming mechanism operable upon the yielding of said abutment, an oscillating bundle transfer movable toward and away from the said bundle forming 70 mechanism, and means operated by the movement of the bundle transfer away from the said bundle forming mechanism for restoring the said abutment.

3. In a harvesting machine in combination, a yielding abutment, feed mechanism for moving loose grain against said abutment, bundle tying mechanism, means operable upon the yielding of the said abutment for actuating the bundle tying mechanism 80 and arresting the action of the said feed mechanism, means actuated by the bundle tying mechanism for arresting the actuation of such mechanism and renewing the operation of the said feed mechanism, an oscillating bundle transfer movable toward and away from the bundle tying mechanism, and means operated by the movement of the bundle transfer away from the bundle tying mechanism for restoring the said abutment. 90

4. In a harvesting machine in combination, intermittently operable bundle tying mechanism having a definite cycle of movement, means for driving the said bundle tying mechanism including a continuously 95 rotating ratchet, a wheel and a pawl carried by the wheel for engaging the ratchet, a pawl lifter engageable with the pawl at a fixed point in the revolution of the said wheel, means for rendering the pawl lifter 100 inoperative and means actuated by the bundle tying mechanism before completing its said cycle of movement for resetting the said pawl lifter.

5. In a harvesting machine in combination, intermittently operable bundle tying mechanism having a definite cycle of movement, feed mechanism, means for simultaneously arresting the action of the feed mechanism and actuating the bundle tying 110 mechanism, and means actuated by the bundle tying mechanism before completing its said cycle of movement for renewing the actuation of the feed mechanism.

LOUIS ANDERSON.
